FIG. 5.

FIG. 6.

Inventor
Peter Barletta

By his Attorneys

C. Garofalo & Co.

UNITED STATES PATENT OFFICE.

PETER BARLETTA, OF LYNDHURST, NEW JERSEY.

ALARM-CLOCK.

1,350,693.

Specification of Letters Patent. Patented Aug. 24, 1920.

Application filed September 6, 1919. Serial No. 322,117.

To all whom it may concern:

Be it known that I, PETER BARLETTA, a citizen of Italy, and residing at Lyndhurst, in the county of Hudson and State of New Jersey, have invented certain new and useful Improvements in Alarm-Clocks, of which the following is a specification, such as will enable those skilled in the art to which it appertains to make and use the same.

10 This invention relates to alarm clocks, and particularly to devices of this class designed to be used in the home, and the object of the invention is to provide an alarm clock which is automatically and electrically operated; a further object being to provide means whereby an electric-light bulb positioned about the face of the clock may be illuminated at any time; a still further object being to provide another light bulb which may be automatically illuminated when the electric alarm is automatically sounded; and with these and other objects in view the invention consists in a device of the class and for the purpose specified, constructed and operating as hereinafter described and claimed.

20

25

The invention is fully disclosed in the following specification, of which the accompanying drawing forms a part, in which the separate parts of my improvement are designated by suitable reference characters in each of the views, and in which:—

Figure 1 is a front view of my improved clock;

Fig. 2 a side view thereof;

Fig. 3 a plan view;

Fig. 4 a back view showing part of the construction broken away;

Fig. 5 a diagrammatic view of an ordinary alarm clock showing my electrical connection therewith; and

Fig. 6 a diagrammatic view of the electrical connections of the complete device.

In Figs. 1 to 4 inclusive, I have shown at 10 my improved clock device in its assembled position, said device consisting of a box-shaped casing 11, closed at the front, opposite sides, and top and bottom, and the back of which is open as shown at 12 and provided with a hinged door 13 held in a closed position by a catch device 14. Within the casing 11 is a shelf member 15 which divides the compartment of said casing into top and bottom chambers 16 and 17 which open backwardly and are closed by the hinged door 13.

The top of the casing 11 is provided with an upstanding clock supporting member 18

provided with a circular aperture 19 in which an ordinary alarm clock 20 is mounted, the feet 21 of said clock resting upon the top of the casing 11, as clearly shown in Fig. 4. The alarm clock 20, as stated, is of the usual form and construction, and is provided with an alarm which is set and operated in the usual manner.

In practice, I place in the chamber 16 and upon the shelf 15 a battery 22, and secured to the bottom of the shelf 15 and within the chamber 17 is an electric bell 23. An electric light bulb 24 is mounted in the top 70 wall of the casing 11 centrally of and in front of the clock supporting member 18, as clearly shown in Figs. 1 and 2, and another electric light bulb 25 is suspended from a hook-shaped arm 26 secured to the 75 back of the clock supporting member 18 and bent upwardly, forwardly and downwardly to bring the bulb over and in front of the top portion of the clock 20 as clearly illustrated in Figs. 1 and 2.

80

Mounted on the top of the casing 11 rearwardly of the member 18 is a switch device 27 which operates in connection with two contacts 28 and 29. Another switch device 30 is mounted on the back of the member 18 and adjacent to the top of the casing 11 as shown in Fig. 4, and is adapted to operate in connection with a contact 31 to open and close the circuit to the electric light bulb 25.

Two binding posts 32 and 33 are mounted 90 in one side wall of the casing 11 and with which a push button switch device 34 is connected through wires 35 and 36. I also preferably mount within the clock 20, or the casing thereof, an electric contact device 37 95 which is adapted to make contact with a spring arm 38 usually employed in alarm clocks, which arm is automatically released to make contact with the contact device 37 when a predetermined hour at which the 100 alarm was previously set is reached for the purpose of automatically sounding the bell 23 as hereinafter set out.

The electric wiring of my improved clock device will be readily understood on a consideration of Fig. 6 from which it will be seen that the pole 39 of the battery 22 is placed in communication with the contact device 37 within the clock 20 through a wire 40 and another wire 41 is connected with 110 one of the legs 21 of the clock and with the contact 29 of the switch 27. A wire 42 is also connected with the pole 39 of the battery and with the binding post 33.

Connected with the other pole 43 of the battery is a wire 44 which connects with the alarm 24, and another wire 45 is connected with said alarm and with the binding post 5 32. A wire 46 connects with the binding post 32 and with the contact 28 of the switch 27. A wire 47 is also connected with the pole 43 of the battery and with the pivoted end 48 of the switch 30. A 10 branch wire 49 is connected with the wire 47 and one pole of the bell 23, while another wire 50 connects with the other pole of said bell and with the pivoted end of the switch 27. Another wire 51 connects 15 with the pivoted end of the switch 27 and with the contact 31 of the switch 30, and in which wire the electric light bulb 25 is placed.

The foregoing completes the wiring of 20 my improved clock device and on a consideration thereof, it will be seen that with the switches 27 and 30 in the position shown in Fig. 6, the electric light bulb 24 may be illuminated at any time by operating the 25 push button switch 34 which closes the circuit through the wires 35, 36, 42, 44 and 45. If the switch 27 be moved into connection with the contact 28 and the push button switch 34 operated, it will be seen 30 by tracing the circuit that the light 24 will be operated and the bell 23 sounded, and by closing the switch 30 the same operation of the push button switch 34 will also illuminate the light bulb 25. It will be seen 35 that the above described sounding of the bell 23 will be independent of the clock 20, or the mechanism therein. By leaving the switch 30 open and moving the switch 27 into engagement with the contact 29, and 40 by setting the alarm clock 20, or the alarm setting mechanism thereof, at the hour of 3 o'clock for example, it will be seen, by tracing the circuit, that when the clock reaches the designated hour, the circuit 45 through the wires 40 and 41 will be automatically closed through the contact device 37 and spring arm 38 within the clock 20 and the bell 23 will be sounded. By closing the switch 30 prior to the above operation, 50 the light 25 will automatically be illuminated when the bell 23 is sounded, and the operation of said bell and the illumination of said light will continue until the switch 27 has been opened or the alarm setting 55 mechanism of the clock moved into a different position.

In short, as will be seen, there are six distinct functions or operations that can be produced by the clock device, as above described. First, the clock may be used in the manner of an ordinary alarm clock independent of the battery, bell, bulbs, etc. Second, the bulb 24 may be illuminated at any time. Third, the bulb 24 and bell 23 60 may be both operated at one time. Fourth, 65

the light 25 operated in combination with the light 24 and bell 23. Fifth, the bell 23 may be automatically sounded independently through the contact 27 and spring arm 38 within the clock 20. Sixth, the light 70 25 may be automatically illuminated in the last named operation.

It will also be apparent that while I have shown a certain form of clock casing and a specific arrangement of the various 75 mechanism of the device, my invention is not necessarily limited to these details, and various changes in and modifications of the construction herein shown and described may be made, within the scope of the 80 appended claims, without departing from the spirit of my invention or sacrificing its advantages.

Having fully described my invention, what I claim as new and desire to secure by Letters Patent, is:—

1. An electric alarm device of the class described comprising a source of electrical supply, an alarm clock in electrical connection therewith, means within the clock for 90 making and breaking the circuit thereto, a light bulb in circuit with said source of electrical supply, a switch for opening and closing said circuit, an electric bell in circuit with said source of electrical supply, and a 95 switch device for closing the circuit to said bell in two different positions thereof.

2. An electric alarm device of the class described comprising a source of electrical supply, an alarm clock in electrical connection therewith, means within the clock for 100 making and breaking the circuit thereto, a light bulb in circuit with said source of electrical supply, a switch for opening and closing said circuit, an electric bell in circuit 105 with said source of electrical supply, a switch device for closing the circuit to said bell in two different positions thereof, another light bulb in circuit with said source of electrical supply, and a switch device for 110 controlling said last named circuit.

3. An electric alarm device of the class described comprising a clock, an electric bell, and electric light bulbs all placed in 115 electric circuits, a switch device for controlling the circuits to said bell and clock, another switch for controlling the circuit to one of said bulbs, and a switch device for controlling the circuit to the other of said bulbs, the first named bulb and said bell.

In testimony that I claim the foregoing as my invention I have signed my name in presence of the subscribing witnesses this 30th day of August, 1919.

PETER BARLETTA.
